(57) CLAIM

The ornamental design for a flower holder and integrated crypt cover fastening rosette, as shown and described.

DESCRIPTION

FIG. 1 is a top, front, right side perspective view of a flower holder and integrated crypt cover fastening rosette showing my new design; and,

FIG. 2 is a bottom, back, left side perspective view thereof. The broken line showing of a rosette is included for the purpose of illustrating environment and forms no part of the claimed design.
